UNITED STATES PATENT OFFICE.

JACOB DARRE JENSSSEN, OF NEW YORK, N. Y., ASSIGNOR TO G. D. JENSSSEN COMPANY,
OF NEW YORK, N. Y.

MEANS FOR PRODUCING ACID LIQUOR IN SULPHITE PULP PROCESSES.

Application filed February 24, 1925. Serial No. 11,338.

To all whom it may concern:

Be it known that I, JACOB DARRE JENSSSEN, a subject of the King of Norway, and residing at New York, in the State of New York, in the United States of America, have invented a new and useful Improvement in Means for Producing Acid Liquor in Sulphite Pulp Processes, of which the following is the specification.

The invention relates to means for producing acid liquor in sulphite pulp processes and the objects of the invention are to eliminate the necessity of heating the water used in the production of the acid liquor during the colder months of the year, when the temperature of the water is so low as to materially retard the reaction incidental to the making of the liquor; to utilize the waste heat generated in the operation of cooking in the sulphite pulp process and distribute the same to the best advantage; to effect economy in the consumption of fuel as well as labor attention and maintenance required in heating the water for the acid liquor tanks; to increase the efficiency of the sulphite pulp processes by improving the quality of the liquor used; and generally to provide in the pulp industry a reduced cost of production and a uniform quality of the output, and it consists essentially of any means employed for the transference of the relief from a pulp digester to the acid liquor towers.

The drawing is a diagrammatic view showing the towers and receptacles in section.

It is well known that the acid liquor used for digesting purposes is an acid solution of calcium magnesium bi-sulphite made from SO_2 gases, water and limestone.

The usual process is carried out in towers containing broken limestone through which water trickles absorbing the SO_2 gases rising from the bottom and collecting and absorbing a lime base which is commonly called "combined."

The water to effectively permit the reaction must not be chilled; else the combining of the elements is so slow as to effect the quality of the liquor, therefore it is customary in approximately seven months of the year to heat the water used.

The heating of the water specially for the acid liquor process is an additional step as well as a considerable drain on the hot

water resources and besides there is a lack of uniformity in the temperatures that is not by any means conducive to the best results.

The present invention utilizes the heat from the digester 10 in bringing the temperature of the water in the acid liquor up to the desired degree of heat.

The relief pipe 11 from the exhaust outlet 12 of the digester 10 leads to the reclaiming tank 13 and extends downwardly thereinto and communicates with and supports the distributing nozzle 14 having many jet orifices 15 and adapted to distribute the acid laden fluid in said tank. A cooler 16 is connected by the pipes 17 and 18 with the pipe 11 intermediate of its length for use, when it is desirable in warmer weather to cool the reclaimed acid liquor and for this purpose the valve 19 is introduced in the pipe line 11 between the connections to the pipes 17 and 18, therefore when the valve 19 is turned to the open position, the cooler is cut out from the operation and its own connection is cut off by the valves 20 and 21 in the pipes 17 and 18.

The acid liquor making towers 22 and 23 are respectively the primary and secondary towers known in the trade as weak and strong towers and the acid liquor is made in these towers as generally described hereinbefore by the process well known in the art, though for the purpose of clearly explaining this invention a one way system is shown, whereas the towers are generally reversible, but this does not alter the main feature of this invention merely adds to the piping and valves.

The plain water is preferably drawn from the lead coolers of the sulphur burning plant and enters the tower 22 and 24 and trickles down through the limestone therein gathering the gas from the sulphur burning plant pressed into the tower by a fan.

The acid liquor resulting from this step flows from the outlet 25 at the lower end of the tower 22 into the pipe 26, which leads to the mixing box 27.

This mixing box 27 is also connected to the reclaiming tank 13 by the pipe 28, therefore the warm acid liquor flows through the pipe 28 and mixes with the cold acid liquor flowing into said box 27 through the pipe 27.

The inlet of the pump 29 is connected to the outlet 30 of the mixing box 27 by the

pipe 31 and the outlet of the pump is connected by the pipe 32 to the upper end of the tower 23 and this pump 29 forces the moderated mixtures from the mixing box

- 5 27 into said tower 23 to trickle down through the limestone and gather the gases rising from the inlet 33 which is connected to the sulphur burning plant. The exhaust gas from the tower 23 is conveyed through the
- 10 pipe 34 from the upper end of said tower 23 to the lower end of the tower 22 for absorption into the fresh water.

The pump 35 is connected to the lower end of the tower 23 by the pipe 36 and to the reclaiming tank 13 by the pipe 37 and the liquor forced thereby from the tower 23 into the reclaiming tank 13, to be strengthened by the relief gases from the digester 10, as only a comparatively small portion of the contents of said tank 13 is used for warming the acid liquor in process of the making.

The finished acid liquor is drawn off from the reclaiming to the storage tank 38 or distributed direct to the digesters as found convenient and desirable.

It will now be seen that by the diversion of the weak acid liquor from its tower to the mixing chamber before reaching the finished tower the temperature of the liquor is moderated, consequently the liquor trickling through the limestone of the second tower readily gathers the lime base and quick reaction occurs due to the moderate temperatures whereby the process is not retarded. In place of this happening the temperature of the weak liquor is so regulated that the absorption and chemical union is encouraged and an affinity established such as would occur under natural conditions during warmer weather conditions when the elements of nature unite under more or less even temperatures.

What I claim is:

45 1. A means for producing acid liquor in sulphite pulp processes comprising a primary tower for the preliminary step and secondary tower for further treatment, and a mixer for heating the liquor in passage from the primary tower to the secondary for the aforesaid further treatment.

50 2. In means for producing acid liquor in sulphite pulp processes, weak and strong liquor towers, a digester, a reclaiming tank connected to the exhaust from said digester, a mixing box forming an intermediary mem-

ber between said weak liquor tower and said reclaiming tank on the one hand and said strong liquor tower and said reclaiming tank on the other hand, means for forcing the heated mixture from said mixing box to said strong liquor tower, and means for drawing the liquor from said strong liquor tower to said reclaiming tank.

3. In means for producing acid liquor in sulphite pulp processes, weak and strong liquor towers, a digester having an exhaust pipe extending from the upper end thereof, a cooling box forming a by-pass in said exhaust pipe under suitable valve control, a reclaiming tank connected to the exhaust from said digester, a mixing box forming an intermediary member between said weak liquor tower and said reclaiming tank on the one hand and said strong liquor tower and said reclaiming tank on the other hand, means for forcing the heated mixture from said mixing box to said strong liquor tower, and means for drawing the liquor from said strong liquor tower to said reclaiming tank.

4. In means for producing acid liquor in sulphite pulp processes, a primary producer, an intermediary mixing chamber receiving the discharge from said primary producer, a secondary producer receiving the discharge from said intermediary chamber, a reclaiming tank feeding said intermediary chamber and receiving the discharge from said secondary producer and a digester exhausting into said reclaiming tank.

5. In means for producing acid liquor in sulphite pulp processes, a weak acid tower and a strong acid tower, said strong acid tower having an exhaust gas connection leading to the lower end of said weak acid tower, an intermediary member forming the liquor connection between said towers, a digester and intercommunicating means furnishing the heat from the exhaust of the digester to said intermediary member.

6. In means for producing acid liquor in sulphite pulp processes, a weak acid tower and a strong acid tower having a gas connection, a digester, a tank common to the exhaust of said digester and the discharge of said strong tower, and means connecting said common tank and said weak tower including a mixing chamber.

Signed at New York, N. Y., U. S. A., this 13th day of January 1925.

JACOB DARRE JENSSSEN.
